SHOE LAST

Julius R. Bindner and Purne A. Cooley,
Mattoon, Ill.

Application March 1, 1933, Serial No. 659,036

14 Claims. (Cl. 12—141)

This invention relates to shoe lasts, and has special reference to shoe lasts of the type having the bottom provided with a metallic surface having openings through which tacks may be driven into 5 penetrable bodies to secure the insole to the last.

Heretofore penetrable plugs have been mounted in cavities in the last opposite the openings through the metallic surface to receive the tacks and certain types of retaining means to retain 10 the plugs have been used. However, when the last is repeatedly used and tacks are repeatedly driven in and withdrawn, the penetrable plugs are eventually damaged and weakened to such an extent that they will no longer satisfactorily retain 15 the tacks. It is then necessary or desirable to remove the penetrable plugs and replace them with others that have not been damaged or destroyed but which will receive and hold the tacks by which the insole is attached to the last. These 20 operations of removing the damaged penetrable plugs and replacing them with others that have not been damaged, but which will receive and retain the tacks securing the insole to the last, have been attended by numerous difficulties and 25 in some cases with unsatisfactory results.

An object of the present invention is to provide an improved penetrable plug and support therefor that may be easily placed in the cavity of a last in and opposite the opening through 30 the metallic surface of the last, in combination with means for holding the penetrable plug in proper position to receive the tacks whereby the insole is attached to the last.

Other objects of the invention will be readily 35 apparent from the following description, reference being made to the accompanying drawing, in which—

Fig. 1 is a perspective view of a last having our 40 invention embodied therein.

Fig. 2 is a vertical cross sectional view of the heel portion of the last on the line 2—2 of Fig. 1.

Fig. 3 is a vertical longitudinal sectional view of the heel portion of the last on the line 3—3 of Fig. 1.

Fig. 4 is a horizontal cross sectional view of the heel portion of the last on the line 4—4 of Fig. 2.

Fig. 5 is a vertical cross sectional view of the forepart of the last on the line 5—5 of Fig. 1.

Fig. 6 is an outer plan view of the metallic plate that is attached to the heel portion of the last constructed and designed to cooperate with the present invention.

Fig. 7 is a plan view of the opposite side of the 55 metallic plate that is shown in Fig. 6.

Fig. 8 is a perspective view of one of the penetrable plugs and the container therefor, constituting an important feature of the present invention.

Fig. 9 is a plan view of a plate designed and 60 adapted to be inserted, in repairing an old last, in an opening in the metallic plate that is attached to the bottom of the last and provided with means for engaging and holding the support for the penetrable plug. 65

Specifically the type of last shown is designed and adapted for use in making McKay shoes. These lasts usually comprise a forepart 1 and a separate heel portion 2, both made of wood and connected together by a hinge pin 3, 70 whereby the last may be broken to extended or angular position.

The under surface of the forepart 1 of the last is covered by a metallic plate 4 attachably secured thereto by removable and replaceable 75 fasteners comprising screws 5 and nails 6. And the under surface of the heel portion 2 of the last is covered by a metallic plate 7 secured thereto by removable and replaceable screw fasteners 8 and nails 9. 80

As shown, the heel portion 2 of the last is formed with a recess 10 larger than the hole 11 through the plate 7 and opening into a well 12 in the body of the heel portion 2 which well is of less diameter than the recess 10. The marginal portion 13 of the plate 7 around the opening 11 extends into the recess 10 and is provided with opposite notches 14. 85

A metallic plate 15 is attached to the plate 7 within the recess 10 by fasteners 16 and has an 90 opening communicating with the opening 11 and notches 17 communicating with the notches 14. This plate 15 is split to provide two opposite resilient arms 18 extending away from the plate 7 and toward the bottom wall of the recess 10. 95 And the terminal portions of the arms 18 are bent to provide notches 19 (Fig. 3).

Our invention comprises a cartridge or shell 20 of approximately the same diameter as the diameter of the opening 11, so that said cartridge 100 or shell may be extended through said opening 11 and through the recess 10 into the well 12. A circumferential flange 21, in connection with the outer end of the cartridge or shell 20, will seat against the marginal portion 13 of the plate 7 105 around the opening 11, the outer surface of said flange 21 being approximately flush and even with the surrounding surface of the plate 7. This cartridge or shell has a pair of pins 22 projecting from diametrically opposite sides and ca- 110

pable of passing through the notches 14 and 17, so that, when the cartridges turn, these pins will engage and rub against the surfaces of the arms 18 and flex said arms toward the plate 5 7 and then seat in the notches 19 formed in said arms. Thus, the power and resiliency of the resilient arms 18 are utilized to engage the pins 22 and thereby hold the cartridge 20 securely in connection with the last. The cartridge 10 20 is filled with a body 23 of penetrable metal, such as lead or other penetrable substance, into which a tack driven through the insole may be driven to attach the insole to the last.

Another one of these removable and replaceable 15 penetrable plug holders is shown connected with the rear of the forepart 1 of the last, and similar reference numerals are applied to visible parts thereof.

Another one of these removable and replaceable 20 plug holders is shown attached to the front of the forepart 1 of the last. As there shown, a disc 24 is mounted in a hole cut in the plate 4. And the disc 24 is of larger diameter than the recess 25 which corresponds to the recess 10, 25 so that the marginal portion of the disc 24 seats against the under side of the forepart 1 of the last. This disc may be attached in this position by fasteners 26 extending through the disc and into the body of the forepart 1, and also by spotwelds 27. The fasteners 26 and the spotwelds 30 27 may both be used, or either may be used without the other, as desired.

This disc 24 is formed with a central opening 28 having a marginal portion 29 provided 35 with opposite notches 30 through which the pins 19 of a cartridge or shell 20 may pass to permit the flange 21 to seat against the inwardly extended marginal portion 29 while the pins 22 engage the resilient arms 18 of the plate 15 attached to the concealed side of the disc 24.

It is now clear that our invention comprises a 40 penetrable body and a support therefor, in combination with means whereby said support may be attached to and detached from a last, and the last easily and quickly repaired and conditioned 45 for further use when the preceding penetrable plugs have become useless. The construction, arrangement and relationship of the parts may be varied within the scope of equivalent limits 50 and otherwise than in the particulars specifically indicated.

We claim:

1. In a last having a well therein and a metallic 55 plate attached to the bottom of the last and having a hole opening into said well, a supporting member extending through said hole and into said well, resilient means having detachable connection with and holding said supporting member in said hole and in said well, and a body of penetrable material supported by said supporting member.

2. In a last having a well in the under side thereof and a metallic plate attached to the bottom of the last and provided with a hole opening 60 into said well, an upwardly extended seat integral with the marginal portion of said plate around said hole, a supporting member removably mounted in said hole and extending into said well and engaging the outer side of said seat, a body of penetrable material in said supporting member, and a latch device in connection with said plate engaging and holding said supporting member in said 65 position.

3. In a last having a metallic plate attached to 70 the bottom thereof and having a hole through

said plate opening into a well in said last, a pair of resilient arms in connection with the side of said plate that is toward said last, a penetrable plug extending through said hole and into said well, and means supporting said plug and engaging said arms to hold said plug in said position. 80

4. In a last having a well therein and a metallic plate attached to the bottom of the last and having a hole opening into said well, an upwardly extended seat in connection with said plate around said hole, a pair of resilient arms attached to the upper side of said plate, a shell extending through said hole and into said well and having a circumferential flange engaging said seat and limiting extent of movement of said shell through said hole and into said well, means in connection with said shell and engaging said arms for holding said shell in said position, and a penetrable body in said shell. 90

5. In a last having a well therein and having a metallic plate attached to the bottom of the last and provided with a hole opening into said well, an upwardly extended seat in connection with the marginal portion of said plate around said hole, a shell extending through said hole and into said well and having an open outer end, a circumferential flange in connection with the outer end of said shell engaging said seat and limiting extent of movement of said shell through said hole and into said well, a body of penetrable material in said shell and extending to the open outer end thereof, and resilient arms in connection with the upper side of said plate engaging and holding said shell in said position. 100

6. In a last having a metallic plate attached to the bottom thereof and provided with a hole opening into a well in the last, a pair of resilient arms in connection with the upper side of said plate adjacent to said hole, a penetrable plug, and means supporting said plug and extending through said hole and into said well and engaging said resilient arms to prevent outward movement of said shell from said hole and said well. 110

7. In a last having a well therein and a metallic plate attached to the bottom of the last and provided with a hole opening into said well, a penetrable plug extending through said hole and into said well and having its outer end approximately even with the outer surface of said plate, arms in connection with the upper side of said plate adjacent to said hole, and lateral projections in connection with said plug engaging said arms and preventing outward movement of said plug. 120

8. In a last having a well therein and a metallic plate attached to the bottom of the last and provided with a hole opening into said well, a penetrable plug extending through said hole and into said well and having its outer end approximately even with the outer surface of said plate, arms in connection with the upper side of said plate adjacent to said hole, and lateral projections in connection with said plug engaging said arms and preventing outward movement of said plug, said plug being rotative to disengage said projections from said arms and said plate having notches from which said projections may pass outwardly to permit detachment of said plug. 130

9. A last having a well therein, a metallic plate attached to the bottom of said last and having an enlarged hole, a metallic disc mounted in said hole in said plate and against the bottom of the last and having a hole opening into said well, means for securing said disc in said position, a pair of resilient arms attached to the upper side of said disc adjacent to said hole, a shell extend- 140

145

150

- ing through said hole and into said well and having an open outer end, a penetrable plug in said shell, and means on said shell and engaging said arms for supporting said shell in position in which the outer end of said plug is approximately even with the outer surface of said disc and said plate. 80
10. A last having a recess in its under side and a well opening into said recess, a metallic plate attached to the bottom of the last having an opening into said recess and said well, arms attached to said plate in said recess, a shell extending through said hole and said recess and into said well and having an open outer end, a penetrable plug mounted in said shell, means limiting extent of inward movement of said shell, and means in connection with said shell and engaging said arms in said recess limiting extent of outward movement of said shell. 85
11. In a last having a recess in its bottom and a well opening into said recess, a metallic plate having a hole opening into said recess and said well, a seat in connection with the marginal portion of said plate around said hole extending into said recess, a shell extending through said hole and said recess and into said well and having an open outer end, a flange in connection with the outer end of said shell engaging said seat, arms in connection with said plate within said recess, projections in connection with said shell engaging said arms, said shell being rotative to engage said projections with and disengage said projections from said arms and said plate having notches through which said projections may pass outwardly, and a penetrable plug in said shell and having its outer end approximately even with the outer surface of said plate. 90
12. As an article of manufacture, a penetrable plug adapted to be inserted in and withdrawn from a recess in a shoe last, comprising a shell having a circumferential flange in connection with its outer open end, a body of penetrable material in said shell, and two pins projecting outwardly from opposite sides of said shell and spaced inwardly from said flange. 95
13. In a last having a well therein and a metallic plate attached to the bottom of the last and having a hole opening into said well and having notches at the sides of said hole, resilient arms attached to the upper side of said plate and spaced from said notches, a shell rotative in said hole and in said well and having a circumferential flange engaging the outer surface of the marginal portion of said plate around said hole, a body of penetrable material in said shell, and projections extending from said shell and engaging said arms, said shell being rotative to disengage said projections from said arms and withdrawable outwardly from said well when said projections are in alignment with said notches. 100
14. In a last having a well therein and having a metallic plate attached to the bottom of the last and provided with a hole opening into said well and having a recess opposite and of larger diameter than said hole and opening into said well, resilient arms attached to the inner side of said plate in said recess, a shell extending through said hole and said recess and into said well, means limiting extent of inward movement of said shell, projections in connection with said shell engaging said resilient arms and cooperating therewith to hold said shell in stationary position, and a penetrable plug in said shell. 105
